UNITED STATES PATENT OFFICE.

RUDOLPH EBERHARD, OF STOCKTON, CALIFORNIA.

LEVELING INSTRUMENT.

No. 915,084.

Specification of Letters Patent. Patented March 16, 1909.

Application filed September 8, 1908. Serial No. 451,466.

To all whom it may concern:

Be it known that I, RUDOLPH EBERHARD, a citizen of Switzerland, residing at Stockton, in the county of San Joaquin, State of California, have invented certain new and useful Improvements in Leveling Instruments; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in leveling instruments used for leveling land for irrigation, planting or other purposes, the object of the invention being to produce an instrument which any person can handle without the necessity of the use of fine and delicate surveying or leveling instruments such as are now used. Also to produce an instrument which is simple and inexpensive of construction and yet especially effective and adaptable for the purpose for which it is designed. This object I accomplish by means of a flexible hose of sufficient size to permit an easy flow of liquid, preferably water, from end to end thereof, said hose being connected with a suitable handle member at each end, such handle members having graduated tubes disposed therein transversely with respect to such hose, said hose and parts being strengthened by means of an interior wire member, the scheme of the invention being to fill such hose with water and then when the ends of said hose are placed at spaced points the water in the tubes will rise to the same level thereby indicating whether the land at such two points is level or not.

Such other and further construction and relative arrangement of parts are also employed as will appear more fully by a perusal of the following specification and claims.

In the drawings similar characters of reference indicate corresponding parts in the several views.

Figure 1 is a side elevation of the complete device. Fig. 2 is a vertical section of the same. Fig. 3 is a section taken on a line 3—3 of Fig. 1. Fig. 4 is an enlarged fragmentary view of a tube and tube holder. Fig. 5 is an enlarged fragmentary view of a

hose and connection showing a strengthening wire therein.

55

Referring now more particularly to the characters of reference on the drawings 1 designates a flexible hose of desired size and length the same being suitably spaced into feet as at 2.

60

3 are handles at each end of the hose 1 and having connecting tips 4 over which the hose 1 fits, there being an orifice 5 in said tip 4 and handle 3 corresponding with the hole of the hose 1 and turning at right angles with 65 said handle 3. A wire 6 extends through the hose 1 to keep it from stretching and is hooked into the tips 4. Screwed into the handles 3 are hollow tube holders 7 coinciding with the holes 5 and having vertical 70 side slots 8 having offset shoulders 9 at their lower ends, said tube holders having bottom shoulders 10 against which rest glass tubes 11 opening into the holes 5 and fixed in position by suitable adhesive material 12, such as 75 white lead, filling around the shoulders 9 and 10. The tubes 11 having removable top corks 13. At the side of the slots 8 on the holders 9 are graduations 14 to indicate the height to which the water rises in the 80 tubes 11.

85

In practice one of the corks 13 is removed and the hose 1 filled with liquid. Then the tubes at its ends are carried to the different points of the land to be leveled and such 85 tubes are raised or lowered until the water stands at the same level in each as indicated by the graduations 4 and then the distance between such tube and the ground designates the amount of difference in the level 90 of the ground. Should the tubes 11 become broken they can be easily removed from the holders 7, and replaced by new ones. The wire 6 prevents the hose 1 from stretching and thus preventing any accurate measurement by the graduations 2.

95

From the foregoing description it will be readily seen that I have produced a leveling instrument which substantially fulfills the object of the invention as set forth herein.

100

While this specification sets forth in detail the present and preferred construction of the device still in practice such deviations from such detail may be resorted to as do not form a departure from the spirit of the invention.

105

Having thus described my invention what I claim as new and useful and desire to secure by Letters Patent is:—

A leveling instrument comprising handle members transparent tubes disposed therein, such handle members having orifices communicating with said tubes, a flexible tube communicating with said orifices, and a wire

extending through said tube and engaging said handle members, as set forth. ¹³

In testimony whereof I affix my signature in presence of two witnesses.

RUDOLPH EBERHARD.
